F. MANKEY.

MOLDING.

No. 17,139.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of **Design No. 17,139**, dated **February 22, 1887**.

Application filed July 1, 1886. Serial No. 206,871. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a band or bar; and it consists in the configuration thereof, substantially as herein shown and described.

On each edge of the bar or band appear regular convexities or scallops A B. The scallops A on one edge are opposite to the scallops B on the other edge. On the face of the bar, and disposed at regular intervals along its center line, are lenticular depressions C. On the face of the bar are channels or grooves D E and F G. Said channels extend from the ends of each lenticular depression to the points of junction of the edge scallops.

The general appearance of my design is that of a series of lenticular figures placed in succession, each figure having the appearance 25 of overlapping the two figures next adjacent to it.

I claim—

1. The design for an ornamental trim or molding, substantially as herein shown and 30 described, which consists in the scallops A B on opposite edges of the trim, and on the face thereof the lenticular depressions C.

2. The design for an ornamental trim or molding, substantially as herein shown and 35 described, which consists in the scallops A B on opposite edges of the trim, and on the face thereof the lenticular depressions C and channels D E F G.

FREDERICK MANKEY.
